UNITED STATES PATENT OFFICE

131,945

DESIGN FOR A PIN OR SIMILAR ARTICLE

Vincent Gambardella, West Haven, Conn.

Application January 1, 1942, Serial No. 104,967

Term of patent 3½ years

To all whom it may concern:

Be it known that I, Vincent Gambardella, a citizen of the United States, residing at West Haven, in the county of New Haven and State of Connecticut, have invented a new, original, and ornamental Design for a Pin or Similar Article, of which the following is a specification, reference being had to the accompanying drawing, forming part thereof.

Fig. 1 is a face view of a pin, or similar article showing my new design; and

Fig. 2 is an edge view of the same.

I claim:

The ornamental design for a pin or similar article substantially as shown.

VINCENT GAMBARDELLA.
